Inventor.

Jerome W. Wetmore

UNITED STATES PATENT OFFICE.

JEROME W. WETMORE, OF ERIE, PENNSYLVANIA, ASSIGNOR TO THE VAN WAGONER & WILLIAMS COMPANY, OF JERSEY CITY, NEW JERSEY.

PNEUMATIC DOOR-CHECK.

SPECIFICATION forming part of Letters Patent No. 502,841, dated August 8, 1893.

Application filed June 25, 1883. Serial No. 99,134. (No model.)

To all whom it may concern:

Be it known that I, JEROME W. WETMORE, a citizen of the United States, residing at Erie, in the county of Erie and State of Pennsylvania, have invented a new and useful Improvement in Pneumatic Door-Checks, of which the following is a specification.

Door checks embodying my invention, belong to that general variety, which are used upon doors, which are provided with springs for closing them, whether said springs be organized as parts of hinges, or separately applied to the door and frame.

One object of my invention, is the production of a simple, compact, and effective pneumatic door-check, having an extensive range of rapid movement as between the piston and its cylinder, and to accomplish these ends, I have for the first time so organized an air cylinder, that it oscillates on a central axis during the swinging movements of a door when controlled by the door check. In other words, my door check includes in combination an air cylinder, a bracket by which said cylinder is supported in a horizontal position for service, and to which said cylinder is centrally pivoted to enable it to oscillate as on a vertical central axis during the swinging movements of a door, a piston sliding in the cylinder, and a piston rod provided with a pivoted arm at its outer end.

Another object of my invention is to provide for a prompt release of compressed air within the cylinder just prior to the complete closure of a door, and this I accomplish for the first time, as I believe, by the combination with the air chamber, of a piston and an automatically operated valve which is opened by the piston just prior to the termination of its air compressing movement, and I have still further provided for variably adjusting the valve operating devices, so that the release of air pressure can be graduated to exact requirements.

After describing my door check improvements in connection with the accompanying drawings, the features deemed novel will be specified in the several clauses of the claim hereunto annexed.

Referring to the drawings, Figure 1; illustrates a door and its frame, with one of my

oscillating cylinder door checks, as applied to operate at the inner side of the door, the latter being shown in an opened position. Fig. 2, illustrates the same parts, with the top 55 of the door frame removed, for showing the door check in top or plan view; and in dotted lines, the positions of the door and the check are indicated, as when the door has been nearly closed. Fig. 3, illustrates the air cylinder 60 in vertical longitudinal section, and containing a piston, its piston rod, and pivoted arm, said piston being of ordinary construction. Fig. 4, illustrates a door-frame and a closed door, provided with a well known 65 form of door spring, and a door check having a non oscillating cylinder containing my automatic valve. Fig. 5, is a top or plan view of the door, its frame, and the door check of Fig. 4. Fig. 6, is an enlarged view of the 70 door check of Fig. 4, detached. Fig. 7, in vertical longitudinal section, illustrates a portion of the air cylinder, its piston, its automatic valve, and its adjusting device.

That portion of my invention which includes the oscillating air cylinder, is illustrated only in Figs. 1, 2, and 3, in which my door check is shown as applied to a door A, and its frame B.

The air cylinder C, is for the first time pivoted so as to oscillate in a horizontal plane, as on a vertical central axis, this latter being afforded by means of trunnion pivots c, c, and a bracket c², and in this case a socket c', serves as a bearing for one of the pivots. The 85 piston G, within the cylinder is provided with a rod D, which occupies a large central opening in the front end C' of the cylinder, and is pivoted at its outer end to the arm E, by means of which, proper connection is made with the 90 door.

As clearly indicated in Fig. 2, the outward swinging movement of the door, to the extent of ninety degrees or a little more, causes the piston to move the entire length of the interior 95 of the cylinder. The inward movement of the piston is very rapid during the early closing movement of the door, but during the terminal closing movement, the piston moves very slowly against the air cushion promptly 100 developed at the outset, by the action of a door spring of any kind, as for instance, the

well known torsional spring S', shown in Fig. 4. The piston G of Fig. 3, with its packing g, valve H, spring I, central opening I', and bail strap F, are all substantially as heretofore.

5 For promptly releasing the compressed air, I have devised an automatic valve, which when applied in its simplest form, affords no external evidence of its presence, and hence it is not shown in all of the figures.

10 In Fig. 7, I illustrate said automatic valve, as employed in connection with any form of door check air cylinder, whether it be arranged to oscillate in accordance with one portion of my invention, or pivoted as heretofore, either at its extreme rear end, or at its extreme front end.

The piston G, has its rod D, coupled thereto by a bail strap F, in a manner well known, and any suitable packing g, is employed for 20 securing close contact with the interior of the cylinder C. There is a port or opening in the piston, covered by a spindle valve H', which is normally held to its seat by a light spring I'. On the front side of the piston, a lever L, 25 is pivoted on a suitable projecting stud. One end of said lever, engages with the valve H', and its opposite end is bent or curved so as to project far beyond the end of the piston, so that as the piston near the end of its stroke, 30 causes the bent end of the lever to strike against the inner or closed end of the cylinder, the valve will be lifted from its seat, and the compressed air permitted to freely escape through the piston into the front 35 portion of the cylinder, and out into the open air through the large opening in the head C', which is only partially occupied by the piston rod. The spring of the valve H', is so light that when the piston is moving outward, 40 air can freely pass through the port to the closed end of the cylinder. It will be seen that in order to render this automatic valve adjustable in its releasing action, the abutting point of the lever must be variable, 45 and I provide for this by the use of an adjusting thumb screw m, entering through the end of the cylinder to afford convenience in manipulation, and the inner end of said screw, serves as the variable abutment with which 50 said lever engages. It will be understood

that this automatically operated releasing valve is applicable to air cylinders hinged as heretofore, as for instance, as illustrated in Figs. 4, 5, and 6, wherein the cylinder is mounted upon an open hinge bracket K, J, 55 having a hinge pin l, and nails or screws j for attaching the whole in position for service.

Having thus described my invention, I claim as new and desire to secure by Letters Patent—

1. In a pneumatic door check, the combination substantially as hereinbefore described, of an air cylinder, a bracket adapted to be applied to a door frame below its top and by which said cylinder is supported in a horizontal position for service, and on which said cylinder is centrally pivoted and capable of oscillating as on a vertical central axis during the movements of a door, a piston, and its rod provided with a pivoted arm at its 70 outer end.

2. In a pneumatic door check, the combination with the air cylinder and its piston, of an automatically operated valve for releasing compressed air, just prior to the terminal air 75 compressing movement of the piston.

3. In a pneumatic door check, the combination with the air cylinder and its piston, of an adjustable automatically operated valve for releasing the air pressure, substantially as 80 described.

4. In a pneumatic door check, the combination of the air cylinder, the piston, a normally closed valve for controlling compressed air, and a lever actuated by the piston for opening said valve, substantially as described.

5. In a pneumatic door check, the combination substantially as described, of the air cylinder, the piston, the normally closed valve thereon, the lever on said piston attached to 90 said valve, and an adjusting screw serving as a variable abutment for contact by said lever during the terminal air compressing movement of the piston, and causing said valve to open for releasing the compressed air.

JEROME W. WETMORE.
